(57) **CLAIM**

The ornamental design for a surgical equipment holder, substantially as shown and described.

DESCRIPTION

FIG. 1 is a perspective view of a surgical equipment holder in accordance with the present invention;

FIG. 2 is an enlarged perspective view thereof taken from area 2 circumscribed in FIG. 1;

FIG. 3 is an enlarged perspective view thereof taken from area 3 circumscribed in FIG. 1;

FIG. 4 is an enlarged perspective view thereof taken from area 4 circumscribed in FIG. 1;

FIG. 5 is a front view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is a rear elevational view thereof.

The short dash-short dash-long dash broken lines depict boundaries of the enlarged views and form no part of the claimed design.

The dash lines depict portions of the surgical equipment holder that form no part of the claimed design.

1 Claim, 10 Drawing Sheets
